UNITED STATES PATENT OFFICE.

JAMES L. SMITH, OF ASHTABULA, OHIO.

CARRIAGE-BOW.

SPECIFICATION forming part of Letters Patent No. 268,436, dated December 5, 1882.

Application filed March 10, 1882. (No model.)

To all whom it may concern:

Be it known that I, JAMES L. SMITH, of Ashtabula, in the county of Ashtabula and State of Ohio, have invented certain new and useful 5 Improvements in Carriage-Bows; and I do hereby declare the following to be a full, clear, and exact description of the invention, such as will enable others skilled in the art to which it pertains to make and use the same.

10 My invention relates to an improvement in carriage-bows, and more particularly to the side pieces thereof, the object being to provide a covering for tubular sheet-metal side pieces which shall combine the qualities of cheapness, durability, and elegance, and which shall add strength to the article covered.

15 With this end in view my invention consists in the combination, with a tubular sheet-metal body, of a cover consisting of strands of flexible material, the same being wound, woven, plaited, or braided over the outer surface of said body.

20 In the accompanying drawings, Figures 1 and 2 represent a carriage-bow provided with a covering applied in accordance with my invention; and Fig. 3 represents a view in cross-section of an improved form of carriage-bow for which I have made application for a patent, said bow being provided with my improved 25 covering.

30 A represent carriage-bows of any desired form of construction and made of any suitable material. They are provided with a covering, B, consisting of strands of cords woven in one case and wound on in the other. After the covering is applied it may be finished or not, as desired. It may, for instance, be coated with paint or varnish, with waterproofing, or with any suitable cement, to bind the strands 35 together. Being loosely applied, the ordinary leather covering for carriage-bows serves only the function of a cover, while my improved 40

cover, being tightly bound on the bow, not only answers as a cover and protection, but it also imparts strength to the bow. In this respect, also, it is superior to the japan covering often applied to metallic carriage-bows, which serves only as a cover, any bending of the bow causing it to crack or peel off. The japan covering is also objectionable in that it is very 45 cold to the hands. To my new carriage-bow (shown in cross-section in Fig. 3 of the drawings) my improved covering is especially applicable, as it completely conceals the joined edges of the bow, imparting to the same a perfectly smooth contour. 50

55 I do not limit myself to any one method of applying flexible strands to carriage-bows, nor do I limit myself to the use of any particular kind of strands. Again, the strands may be simple 60 strands or several twisted or braided together. I would therefore have it understood that I do not limit myself to the exact construction shown and described, but that I hold myself at liberty to make such slight changes and 65 alterations as fairly fall within the spirit and scope of my invention.

Having fully described my invention, what I claim as new, and desire to secure by Letters Patent, is—

70 In a carriage-bow side piece, the combination, with a tubular sheet-metal body, of a cover consisting of strands of flexible material, the same being wound, woven, plaited, or braided over the outer surface of said body, substantially as and for the purpose set forth. 75

75 In testimony whereof I have signed this specification in the presence of two subscribing witnesses.

JAMES L. SMITH.
